CHECKER CHAMBER FOR REGENERATIVE
FURNACES AND THE LIKE

Leon Thomas Petit, Pittsburg, Calif.

Application March 18, 1933. Serial No. 661,624

10 Claims. (Cl. 263—19)

This invention relates to furnaces and more particularly to furnaces using regenerative chambers such as open hearth furnaces, and has for its object the provision of an improved type 5 of regenerative chamber.

Another object of the present invention is to provide means to readily remove and replace the checker brick work in the regenerative chambers.

10 Other objects and advantages will be apparent as the invention is more fully disclosed.

In accordance with the objects of the present invention I have devised a novel type of regenerative chamber in which the checker brick 15 work is supported upon a suitable structural frame that is mounted on wheels, so that they may be withdrawn from the chamber when the checkers require cleaning and removal. New or spare assemblies can then be installed within 20 the chamber as soon as the old ones are withdrawn, thereby providing for the substantial elimination of shut down periods heretofore experienced in these type of furnaces. As a modification of the present invention the entire 25 chamber can be made removable in a similar manner if desired. Before further disclosing the present invention reference should be made to the accompanying drawings wherein—

30 Fig. 1 illustrates in top plan view partly in section of an open hearth furnace assembly of units showing the adaptation of the present invention thereto;

Fig. 2 is a side elevation sectional view along plane 2—2, Fig. 1;

35 Fig. 3 is a sectional view along plane 3—3, Fig. 1;

Fig. 4 shows a modified structure of the invention;

40 Fig. 5 shows a second modified structure of the invention; and

Fig. 6 is a section taken along plane 6—6 of Fig. 5.

In Fig. 1 the regenerative furnace 1, the stack 45 2 and two sets of checker chambers 3 are shown in their typical arrangement. The two sets of chambers are necessary to provide for alternate use through periodic reversal of damper 4 in a manner heretofore practiced in the art. 50 As the present invention relates specifically to the checker chamber 3 and to an improvement therein, further identification of cooperating elements of the assembly is believed not necessary in view of the fact that such elements are 55 well known to those skilled in the art. The op-

eration of the assembly also need not be described.

In accordance with the present invention checker chambers 3 are improved by providing 60 removable checker brick assemblies 5 supported upon wheels 6 (not shown in Fig. 1) engaging in tracks 7. The entire assembly 5 is so constructed that it may be run into the chamber 3 on tracks 7 and sealed therein and thereafter 65 function precisely as checker brick structures 65 heretofore built integrally therein as heretofore in the art. When the checker brick requires 70 cleaning or replacing the seal may be broken, the checker assembly withdrawn and a new one inserted in its place. The time interval required for such operation is relatively short as compared to that required for a complete shut 75 down to repair and replace a checker structure 75 integrally built up within the chamber.

There are many possible adaptations of this 80 broad idea of removable checker brick assemblies and many possible structures thereof. One structure may be noted in Figs. 2 and 3, wherein the checker brick 8 is shown built up with 85 end and side walls 9—9' and 10—10' respectively. The frame of the truck 11 carrying wheels 6 carries also the base 12 of the checker assembly and between the base 12 and checker brick 8 are provided two longitudinally extending passageways 13—13' separated by partition 14. The 90 bottom of the assembly at one end is provided with a conduit 15 to connect passageways 13—13' to flue 16 leading to stack 2. Means such as indicated at 17 to seal the assembly 95 within the chamber 3 is provided.

There are other structural features illustrated but it is believed unnecessary to specifically define the several parts as they are common in the prior art and readily recognizable.

In the modification illustrated in Fig. 4, essentially the same removable checker assembly appears as heretofore described in Figs. 1, 2 and 3 with the new feature of constructing chamber 3 with an arched roof 20 common to both removable checker assemblies contained therein.

In Figs. 5 and 6 I have shown a further adaptation of the present invention wherein the entire checker chamber is built up upon a frame 21 supported by wheels 22 running in tracks 23. 105 The checker chamber consists of side, end, top and bottom walls 24, 25, 26 and 27 respectively with checker brick 28 built up therebetween. A plurality of longitudinally extending flues 29 are 110 provided in the bottom of the chamber between

the bottom of checker brick 28 and bottom 27, the flues 29 communicating at one end with conduit 30 extending downwardly through bottom 27 and communicating with flue 31 leading to stack 2 as before. Outlet opening 32 is adapted to be placed in communication with opening 33 leading to an open hearth furnace 1.

In such an assembly as illustrated in Figs. 5 and 6 an entire checker chamber may be constructed at a point remote from the furnace, placed in position for use, taken away when necessary for repair, and replaced in a relatively short time interval with a new assembly, thereby avoiding extensive and expensive 15 shut down periods.

Having broadly and specifically described the present invention it is apparent that many modifications and departures may be made therein without departing essentially from the nature 20 and scope thereof and all such modifications and departures are contemplated as may fall within the scope of the following claims:—

What I claim is:

1. In a checker chamber for regenerative furnaces and the like, permanently located side, back end and top walls and a separate removable unit consisting of the bottom, front end wall and checker brick assembly of said chamber.

2. In a checker chamber for regenerative furnaces and the like, permanently located side, back end and top walls and a separate assembly of bottom, front end wall and checker brick adapted to be inserted and withdrawn from the 35 said chamber as a unit without disturbing the permanently located walls of said chamber.

3. In a checker chamber for regenerative furnaces and the like, a checker chamber having substantially permanently located side, back end 40 and top walls and a separate checker brick assembly including the bottom and front end walls, said assembly being adapted to be inserted and withdrawn from the said chamber as a unit without disturbing the permanently located walls 45 of said chamber.

4. In a checker chamber for regenerative furnaces and the like, a checker brick assembly

built up as a separate unit upon a base, said base having means thereon to permit a ready insertion and withdrawal of the checker brick assembly into and out of said chamber.

5. In a checker chamber for regenerative furnaces and the like, a checker brick assembly mounted upon wheels as a separate unit and adapted to be readily inserted or removed from the checker chamber.

6. A checker chamber for regenerative furnaces, said chamber being built as a separate unit upon a base frame carried on wheels and adapted to be readily moved into and out of cooperative position with respect to said furnace.

7. A checker brick assembly for checker chambers comprising a base frame supported on wheels, a checker chamber bottom carried by said frame, checker brick work, and a checker chamber end wall built up on said bottom, and a flue opening extending through said bottom communicating with said checker brick work.

8. A checker chamber comprising permanently located side, top and back end walls, a trackway extending thereinto, and a checker brick assembly built up on a frame carried by wheels 100 engaging said trackway and adapted to be positioned within said chamber.

9. A checker chamber comprising permanently located side, top and back end walls, a trackway extending thereinto, and a checker brick 105 assembly including a front end wall for said chamber built up on a frame carried by wheels engaging said trackway, said assembly being adapted to be readily inserted and withdrawn within the chamber.

10. A checker chamber comprising permanently located side, top and back walls, a trackway extending thereinto, a flue opening in the bottom, and a separate checker brick assembly including a front end wall for said chamber 115 built up on a frame carried by wheels engaging said trackway, said assembly being adapted to be readily positioned within said chamber walls to complete the chamber structure with all its cooperating parts and elements.
